UNITED STATES PATENT OFFICE.

DAVID AITKEN, OF LETHBRIDGE, ALBERTA, CANADA.

SAFETY RAZOR.

1,411,552.

Specification of Letters Patent.

Patented Apr. 4, 1922.

Application filed June 7, 1918. Serial No. 238,702.

To all whom it may concern:

Be it known that I, DAVID AITKEN, a citizen of Canada, residing at Lethbridge, in the Province of Alberta and Dominion of Canada, have invented new and useful Improvements in Safety Razors, of which the following is a specification.

This invention relates to safety razors and it consists in the novel features herein-
10 after described and claimed.

An object of the invention is to provide a razor of the character stated which is simple and durable in structure, embracing a minimum number of parts and having the
15 parts so assembled that they may be readily disconnected from each other for cleansing, sharpening the blades or packing in compact space.

A further object of the invention is to pro-
20 vide in a razor of the character stated means whereby the handle may be positioned at a desired angle with relation to the plane in which the blade of the razor lies, consequently the razor may be conveniently used
25 over the face or any part of the body.

A further object of the invention is to provide means for holding the blade during the stropping or sharpening of the same.

In the accompanying drawing:-

30 Figure 1 is an edge view of the razor.

Figure 2 is a side view of the same.

Figure 3 is a plan view of the blade of the razor.

Figure 4 is a plan view of one guard plate
35 of the razor.

Figure 5 is a similar view of the other guard plate of the razor.

Figure 6 is a side view of a stud used in the razor.

40 Figure 7 is a side view of the handle of the razor with parts shown in section.

Figure 8 is a side view showing the parts arranged for holding the blade for stropping or sharpening.

45 Figure 9 is a perspective view of the blade holder.

Figure 10 is a transverse sectional view of the device cut on the line 10—10 of Figure 8.

Figure 11 is a side view of the device for
50 retaining the blade holder.

Figure 12 is a side elevation of the handle.

The razor comprises a blade 1 of usual configuration and which is provided at its opposite longitudinal edges with sharp cutting edges. The said blade 1 is further

provided at its center with a longitudinally disposed slot 2.

A guard plate 3 is adapted to be positioned at the outer side of the blade and is provided with arched portions 4 adapted to pass 60 through the slot 2 of the blade 1. The inner ends of the arched portions are separated or spaced by an opening 5. The razor further includes a guard plate 6 which is provided at its opposite edges with the 65 usual teeth 7. The plate 6 is further provided at its center with a longitudinally disposed slot 8 which is adapted to register with the slot 2 of the blade 1 and is adapted to receive the arched portions 4 of the blade 70 3 when the parts are assembled. The plate 6 is further provided at a point between the ends of the slots 8 with a hump 9 which bridges the slot 8. The said hump is substantially convexo-concaved in config- 75 uration and is provided with a slot 10 having its median longitudinal dimension disposed at a right angle to the corresponding dimension of the slot 8.

The razor further includes a T-shaped 80 stud 11 which is provided with a substantially cylindrical head 12. The head 12 is adapted to lie within the arched portion 4 of the plate 3 and the shank of the stud 11 passes through the opening 5 and 85 the slots 8 and 10. A handle 13 is provided at one end with a threaded socket 14 which is adapted to be screwed into engagement with the shank or stem of the head 11. Therefore when the handle 13 is applied 90 to the stud the plates 3 and 6 and the blade 1 will be clamped in position between the end of the handle and the head 12 of the stud. It is apparent that by loosening the handle 13 upon the stud the handle may 95 be swung at any desired angle with relation to the plane in which the blade 1 lies and when at a desired adjustment may be secured by screwing the handle upon the stud and clamping the parts as hereinbefore 100 indicated.

The handle 13 is provided at that end opposite the end which is provided with the socket 14 with a sleeve 15 having a slot 16 leading into the same from one end 105 thereof. A retaining member 17 is adapted to be used in conjunction with the handle when the same is used for stropping or sharpening the razor blade. One end of the retaining member is adapted to be 110

slipped endwise upon the sleeve 15 and the said end of the said member is provided with lugs 18 which enter the slot 16 whereby the member 17 is restrained against turning 5 movement with relation to the handle when the parts are connected. The member 17 is hollow and is provided at its outer end with a longitudinally disposed slot 19.

A blade holder 20 is adapted to be used 10 in conjunction with the member 17 and the said blade holder is preferably formed from a sheet of metal which possesses more or less resiliency.

The blade holder 20 is provided with a 15 cylindrical portion 21 adapted to fit in the end portion of the member 17 and the said blade holder 20 is further provided with flat portions 22 located at the edges of the cylindrical portion 21 and adapted to pass 20 through the slot 19 of the retaining member 17. One of the flat portions 22 is provided with a slot 23 and the other portion 22 is provided with a hump 24.

The razor blade 1 is adapted to be inserted 25 between the portions 22 and when the slot 2 of the razor blade is in register with the slot 23 of one of the portions 22 the hump 24 of the other portion 22 may pass through the slot 2 of the blade 1 as 30 best illustrated in Figure 10 of the drawing whereby the blade is held in position between the flat portions 22 of the holder

20. The holder is then inserted in position in the end of the retaining member 17 as best shown in Figure 10 of the drawing. Therefore the handle 13 and the parts connected therewith may be easily and conveniently used as means for holding the razor blade 1 while the same is being stroped or sharpened.

Having described the invention what is claimed is:—

A razor comprising a blade having an oblong transverse opening, blade holding members and an integral spring connection between the blade holding members; said members by the inherent resiliency of said connection being held together in opposed relation with the razor blade between them, and one of said members being provided with an oblong opening in registration with the oblong opening in the blade, and the other member being provided with an oblong protuberance pressed laterally beyond the plane of the major portion 55 thereof and occupying the oblong opening in the blade and extending into the oblong opening in the first named member, and the said oblong openings and oblong protuberance being disposed in the direction 60 of the length of the razor.

In testimony whereof I affix my signature.

DAVID AITKEN.
